UNITED STATES PATENT OFFICE.

HARDY B. HOUSER, OF CINCINNATI, OHIO.

FREIGHT-CAR.

No. 900,170.

Specification of Letters Patent.

Patented Oct. 6, 1908.

Application filed December 30, 1907. Serial No. 408,516.

To all whom it may concern:

Be it known that I, HARDY B. HOUSER, a citizen of the United States of America, and resident of Cincinnati, county of Hamilton, 5 State of Ohio, have invented certain new and useful Improvements in Freight-Cars, of which the following is a specification.

My invention relates to a freight car provided with a secondary floor which may be 10 utilized for converting the car into a double deck, or may be placed aside for making the car into a single deck car.

The object of my invention is a car provided with a secondary floor which may be 15 moved from a horizontal position midway between the roof and the main floor to a position adjacent to the roof of the car, or vice versa, which is of a construction such that it does not become stuck in either position during 20 unfavorable weather, such as raining or freezing weather and which, likewise, is of a construction such that it does not interfere with the usual feed racks in the car. This object is attained by the means described in 25 the specification and illustrated in the accompanying drawings, in which;

Figure 1 is a view partly in plan and partly in section of a car embodying my invention, the part upon the left being shown 30 with the roof removed, and the part upon the right being taken upon line $x-x$ of Fig. 3. Fig. 2 is a view partly in side elevation and partly in vertical section upon line $y-y$ of Fig. 3. Fig. 3 is a transverse sectional view taken upon line $v-v$ of Fig. 2. Fig. 4 is a view taken upon line $z-z$ of Fig. 2 but showing one side section of the floor folded as is done in preparing to raise the floor to its uppermost position.

40 Referring to the parts: The secondary floor is composed of a central section consisting of longitudinal boards, A, A', secured to transverse bars, B, and of two side sections consisting of longitudinal boards, A², A³, 45 which are pivoted by means of hinges, C, to the boards, A, A', so as to be capable of being swung to a horizontal position to rest upon the transverse bars, B, and to contact the side walls, D, D', of the car, or to be 50 swung to a horizontal position resting upon top of the boards, A, A'. The boards, A, A', are made of a size such that when the boards, A², A³, are folded inward, the boards, A, A', will pass upward between the

feed racks, d, d', without contacting the same.

To steady the movement of the secondary floor, the transverse bars are notched at their ends, to straddle the vertical side posts, d², d³, of the car body. The movement of the 60 secondary floor is effected by means of cables, e, which are secured at their outer ends to the bars, B, and at their inner ends to the horizontal shaft, E, which is journaled in the rafters, d⁴, of the roof. The movement 65 of the cable is rendered easy by passing over sheaves, e', which are mounted loosely upon longitudinal rods, e², secured at each side of the car in the rafters, d⁴.

The secondary floor is supported in its operative, or its inoperative position by rods, F, bent at ends, f, f', to engage eyelets, g, g', which are screwed into the external posts, d⁵, of the car body. These rods, F, are removable and are placed in the eyelets, g, when 75 the floor occupies its intermediate or operative position, and are placed in the eyelets, g', when the floor occupies its uppermost or inoperative position.

Latches, K, are pivoted to post, d⁵, in a 80 position such that they may be swung inward over boards, A², A³, when the boards are unfolded and in their lowermost position.

Supposing that a car has been used in cold weather with the secondary floor in its operative position for conveying stock. The floor will naturally become stuck to the sides of the car by the freezing of the accumulation of matter thereon. When it is desired to raise the floor, this adherence of the floor 85 to the sides is very readily overcome by an upward blow upon the sections, A², A³, 90 causing them to be folded. The floor may then be raised very readily by engaging the squared end of shaft, E, with a crank and 95 revolving it.

What I claim is:

1. In a freight car the combination of a secondary floor adapted to be laterally extended to a width substantially equal to the 100 inside width of the car and of being reduced to a width smaller than said inside width, a means of supporting the secondary floor in a position intermediate the main floor and the 105 roof of the car and a mechanism for moving the secondary floor to a position adjacent to the roof and of returning it to its intermediate position.

2. In a freight car the combination of a secondary floor consisting of a central longitudinal section and two longitudinal side sections, hinges connecting the side sections to the central section, a means of supporting the secondary floor in a position intermediate the floor and the roof of a car, and a mechanism for moving the secondary floor to a position adjacent to the roof or of returning it to its intermediate position.
3. In a freight car having feed racks located at the sides and top thereof, a secondary floor adapted to be extended to a

width substantially equal to the width of the inside width of the car and of being 15 reduced to a width less than the distance between the feed racks, a means of supporting the secondary floor in a position intermediate the main floor and the roof of the car, and a mechanism for moving the secondary floor 20 to a position adjacent to the roof, or of returning it to its intermediate position.

HARDY B. HOUSER.
